UNITED STATES PATENT OFFICE.

LEE FRASIER AND CONNELL C. HINER, OF WACO, TEXAS.

RIM STRAIGHTENER.

Application filed October 6, 1924. Serial No. 742,032.

This invention appertains to an improved tool for straightening bent and damaged rims of automobile wheels and the primary object of the invention is to provide a novel 5 tool which can be effectively used for quickly straightening out bent tire rims of automobile wheels, the tool embodying novel means for engaging the flanges of both clincher and straight sided rims.

10 A further object of the invention is to provide a novel rim tool formed of a single strip of metal of the desired gauge bent to provide a manipulating handle and the rim engaging portion.

15 A further object of the invention is to provide a novel combination tool of the above character which can have formed on the opposite ends thereof tools of different types for straightening clincher and straight sided 20 rims or which can have formed on one end thereof a rigid jaw wrench for manipulating rim nuts or other parts of an automobile such as spark plugs and the like.

25 A still further object of the invention is to provide an improved rim tool of the above character, which will be durable and efficient in use, one that will be simple and easy to manufacture and one which can be placed upon the market at a small cost.

30 With these and other objects in view, the invention consists in the novel construction, arrangement and formation of parts, as will be hereinafter more specifically described, claimed and illustrated in the accompanying 35 drawings, in which drawings,

Figure 1 is a perspective view of the improved rim tool,

40 Figure 2 is a side elevation of the tool showing the same used for straightening the rims for the type employed for straight sided tires.

45 Figure 3 is an edge elevation of the tool showing the same in use for straightening the flanges of clincher rims one end of the tool being shown provided with a rigid jaw wrench,

Figure 4 is a detail view showing the rigid jaw wrench formed on one end of the tool.

50 Referring to the drawings in details, wherein similar reference characters designate corresponding parts throughout the several views, the letter A generally indicates the improved rim tool, which is preferably formed from forged tool steel and as shown 55 the same includes a flat elongated shank or handle 5 having the head B formed on one

end thereof for engaging and straightening straight sided rims and the head C on the other end thereof for straightening flanges 60 of clincher rims.

If so desired as shown in Figures 3 and 4 of the drawing the tool can be provided at one end with either the head B or C and at its other end with a rigid jaw wrench D for removing the spark plugs and the like 65 from an automobile. The wrench D preferably extends at an angle to the shank as clearly shown in the drawing and forms a handle for manipulating the tool when the same is used for straightening a rim.

70 The head B which is used for straightening rims for straight wall tires embodies a hook 6 which extends in the same plane as the shank 5. As shown the hook 6 is formed by bending the shank back upon itself as 75 at 7 and then bending the bar again to form the bill 8 of the hook. In forming the head B the shank 5 is bent slightly to an angle to the main portion of the shank so that the hook 6 will extend in parallel relation to the 80 shank.

75 In use of the tool the hook is applied to the straight side of the rim as shown in Figure 2 of the drawing in such a manner that the bent portion thereof will be firmly gripped in the bend of the hook and by manipulating the shank 5 thereof in the desired direction the bent portion of the flange can be readily forced back in place. The straight sided rim is indicated by the 85 reference character E in Figure 2 of the drawing and is of the usual construction provided with the side flanges 9 for engaging the straight walls of a tire.

90 The head C which is utilized for straightening clincher rims comprises a hook 10 which is formed by bending one end of the shank 5 back upon itself as clearly shown 95 in Figures 1 and 3 of the drawing. The bill of the hook extends in parallel relation to the shank 5 and is preferably sharpened 100 as at 11 to facilitate the placing of the hook in position.

105 A clincher rim is shown in Figure 3 of the drawing and is indicated by the reference character F and this rim is of the usual type provided with the inwardly bent flanges 12.

110 In use of the tool for straightening the rims of the clincher type, the hook 10 of the head C is placed over the bent portion of the flange of the rim as shown in Figure 3

of the drawing and the tool is now used as a lever for bringing the bent place back in position.

In numerous instances the rims of the 5 automobile become bent and distorted due to the driving thereon when the tires become deflated and with the use of the tool as shown, the rims can be readily repaired.

Changes as to details may be made without departing from the spirit or the scope 10 of this invention, but:—

What we claim as new is:—

As an article of manufacture, a tool for bending the flanges of vehicle wheel rims 15 and restoring the same to a normal state

comprising a flat elongated body formed with a hook at one end thereof, the end of the body carrying the hook being directed at an angle to the said body and being bent inwardly upon itself in engagement with 20 the body and then forwardly in spaced parallel relation to the body to form the bill of the hook, the said bill of the hook terminating in the same plane with the adjacent end of the body for engaging the flanges of 25 rims for straight wall tires.

In testimony whereof we affix our signatures.

LEE FRASIER.
CONNELL C. HINER.
